UNITED STATES PATENT OFFICE.

RALPH W. ERSKINE, OF PITTSBURG, KANSAS.

BLOW-OFF COCK.

968,037.

Specification of Letters Patent. Patented Aug. 23, 1910.

Application filed March 25, 1910. Serial No. 551,572.

To all whom it may concern:

Be it known that I, RALPH W. ERSKINE, citizen of the United States, residing at Pittsburg, in the county of Crawford and 5 State of Kansas, have invented certain new and useful Improvements in Blow-Off Cocks, of which the following is a specification.

My invention relates to valves and particularly to blow-off cocks such as are used 10 on steam boilers.

The object of the invention is to provide a blow-off cock, the inlet opening of which may be closed, while the main valve is being repaired or replaced.

15 In blow-off cocks as ordinarily made, when it is desired to replace or repair the main valve it is necessary to allow the steam and water to be drawn off from the boiler, as otherwise the steam or water would be 20 blown out of the blow-off cock, while the valve was out of its place. It is to remedy this condition that I have devised my invention, and the invention contemplates providing a main valve stem which is movable 25 in one direction to close or open the main valve and an auxiliary valve, so connected to the main valve stem that when the main valve stem is rotated the auxiliary valve will be closed, it being held in this position 30 by the pressure of steam in the boiler.

For a full understanding of the invention reference is to be had to the following description and accompanying drawing, in which:—

35 Figure 1 is a longitudinal section of the valve-casing and valve, the operating shaft and the auxiliary valve being in elevation. Fig. 2 is a perspective detail view of the eccentric, and Fig. 3 is a perspective detail 40 view of the auxiliary valve operating rod and ring.

45 Corresponding and like parts are referred to in the following description and indicated in all the views of the drawing by the same reference characters.

Referring to these figures 2 designates the body of the shell or blow-off cock, and 3 the tubular extension leading therefrom, and which is screw-threaded at its extremity as 50 at 4 for engagement with the boiler. The end of this extremity is formed with a valve-seat 5 of any suitable character.

55 The shell or body 2 at one end is screw-threaded for engagement with a hub 6 through which the main valve stem passes and screw-threadedly engaged with this hub

is the packing nut 7. The other end of the shell or casing 2 is interiorly screw-threaded for engagement with an annular member 8, screw-threaded on its interior as at 9 for engagement with a pipe connection. This annular member is preferably hexagonal upon its outer face to provide means whereby a wrench may be applied thereto. The inner end of the annular member 8 is formed with 60 a valve-seat 10 against which the valve 15 engages, this seat being preferably beveled.

Passing through the hub 6 and the gland 7 is the valve-rod 11 formed at its lower end with the eccentric 12. This rod 11 at its 70 lower end is detachably engaged with a valve-stem 13 having an enlarged lower portion 14 which fits in a screw-threaded recess in the upper face of the valve body 15. A nut 16 engages with the screw-threaded inner face of the valve body 15 and acts to hold the valve body in engagement with the stem 13. The outer face of the valve body 15 is provided with a stud 17 whereby the valve body may be rotated to easily disengage it 75 from the nut 16. It will be seen that the valve body and the nut 16 are free to rotate upon the stem 13, or in other words are held in swiveled engagement with the stem. The inner end of the stem 13 is screw-threaded for engagement with a screw 80 threaded recess 18 formed in the lower end of the main valve-stem 11.

As a means of closing the inlet through the lateral extension 3 I provide the valve 90 body 19 screw threaded upon a spindle 20, or stem, passing through a guide 21 intersecting the extension 3 which rod or spindle 20 at its end is provided with a ring 22 with which the eccentric 12 loosely engages. A 95 lock-nut 23 holds the valve 19 in any adjustable position on the rod 20.

The purpose of my invention is as follows:—Under ordinary circumstances the eccentric 12 projects in the direction of the 100 extension 3 and hence the rod 20 is held projected and the valve 19 is held clear of the valve-seat 5. The eccentric 12 has a much greater width than the width of the ring 22, and hence the eccentric may be 105 moved through the ring 22. The eccentric is of course operated by the valve-stem 11. By raising or lowering the valve-stem 11 the valve is lowered or raised to or from its seat 10. Any suitable means may be provided for reciprocating the valve-stem 11. I have not illustrated any such means as it 110

will be obvious that a large number of devices might be used for this purpose.

When it is desired to repair the valve 15 or to regrind the valve or the valve-seat, or 5 replace an old valve with a new, it is only necessary to rotate the valve stem 11, thereby drawing inwardly the rod 20 and throwing the valve 19 into contact with the seat 5. In this position, the valve 19 will be held 10 to its seat by the pressure behind it. By now removing the annular member 8 the valve 15 may be easily detached from the stem 11 and removed for regrinding or repairing, or the member 8 may be removed 15 and the seat therein reground. During all this the pressure holds the valve 19 in place against the seat 5. After the valve is replaced in position, and the parts are in their normal condition, the stem 11 is rotated 20 until the valve 19 is forced outward and away from the seat 5.

It will be seen that my invention is very simple, and I have found it in practice to be entirely effective, obviating the usual inconveniences incident to the removal of the blow-off cock valve and eliminating the necessity of drawing the fires, or blowing off the steam and water prior to removing the valve.

30 Having thus described the invention what is claimed as new is:—

1. A blow-off cock having therein a main valve operatively movable in one direction to control the passage through the blow-off 35 cock, and having a portion movable in a plane at right angles to the direction first named, an auxiliary valve operable in a direction at right angles to the first named movement of the main valve, and a connection 40 between said main valve and the auxiliary valve whereby the auxiliary valve may be moved by the second named movement of the main valve.

2. In a blow-off cock, a casing having a 45 main valve seat and an auxiliary valve seat, a main valve operable in one direction, an auxiliary valve operable in a direction at an angle to the direction of movement of the main valve, and a valve-stem operatively 50 connected to the main and auxiliary valves, movable in one direction to operate the main valve, and also operable to close or open the auxiliary valve.

3. In a blow-off cock, a casing having an 55 inlet opening and an outlet opening, a valve-stem passing through the casing and having a valve at its end engaging with the out-

let opening, said valve-stem being rotatable, an auxiliary valve adapted to close the inlet opening, and a connection from said auxiliary valve to the valve-stem whereby the auxiliary valve may be closed by a rotation of the main valve-stem.

4. In a blow-off cock, a casing having an inlet opening and an outlet opening and having a valve-seat at the outlet opening, a spindle passing through the casing carrying a valve at one end and adapted to close against said seat upon a longitudinal movement of the spindle, said spindle and valve being rotatable, an auxiliary valve closing the inlet opening to said casing, a rod connecting said auxiliary valve to the valve-stem, and means on the valve-stem for reciprocating said rod upon a rotation of the valve-stem.

5. In a blow-off cock, a casing having a lateral extension formed with a valve-seat at its end, said casing being provided with a valve-seat at one end, a longitudinally shiftable, rotatable stem passing into the casing, a valve on the end thereof engageable with the valve-seat on the casing, an eccentric carried by said stem, an auxiliary valve adapted to close against the seat on the extension, a rod connected to the auxiliary valve, and a ring on the end of said rod surrounding the eccentric.

6. In a blow-off cock, a casing having a screw-threaded opening at one end and provided with a lateral tubular extension having a valve seat and adapted to be screwed into a boiler, an annular member screw-threaded into said open end of the casing and forming a valve-seat, a longitudinally shiftable, rotatable main valve-stem passing into the casing, an eccentric formed on said stem, a main valve, a connecting stem detachably connected to the main valve stem and detachably connected to the main valve, an auxiliary valve adapted to fit against the valve-seat on the extension, a rod extending from said auxiliary valve through the extension, and a ring on the end of said rod surrounding the eccentric on the said valve stem, said eccentric being fitted to the said ring so as to permit the eccentric to shift longitudinally therethrough.

In testimony whereof, I affix my signature in presence of two witnesses.

RALPH W. ERSKINE. [L. s.]
